CLAIM

The ornamental design for a cap for a pouch, as shown and described.

DESCRIPTION

FIG. 1 is a top perspective view of a cap for a pouch of the present invention;

FIG. 2 is a front view thereof;

FIG. 3 is a side perspective view thereof;

FIG. 4 is a front view thereof;

FIG. 5 is a left side view thereof;

FIG. 6 is a back view thereof;

FIG. 7 is a right side view thereof;

FIG. 8 is a top view thereof;

FIG. 9 is a bottom view thereof;

FIG. 10 is a perspective view of the cap for a pouch of FIG. 1; shown in a position of use with an exemplary pouch

FIG. 11 is a front view thereof;

FIG. 12 is a left side view thereof;

FIG. 13 is a back view thereof;

FIG. 14 is a right side view thereof;

FIG. 15 is a top view thereof; and,

FIG. 16 is a bottom view thereof.

The broken lines are shown for the purpose of illustrating both parts of the article as well as environmental subject matter of an exemplary pouch. None of the broken lines form part of the claimed design.
